UNITED STATES PATENT OFFICE

HENRICH FOCKE, OF BREMEN, GERMANY

AEROPLANE OF DUCK-TYPE CONSTRUCTION

Application filed December 30, 1927, Serial No. 243,728, and in Germany December 30, 1926.

It is known that the side steering of flying machines in aeroplane construction may be effected by pivoting the front wing about an axis of rotation lying approximately in the flying direction. This however gives the disadvantage that the centre of pressure of the front wing tends to be displaced laterally in curves by the difference of speed of the two sides of the wing as also immediately upon the occurrence of a small deviation of longitudinal axis of the machine from the direction of flight "sliding" so that a momentum of the front wing about its axis of rotation lying approximately in the flying direction is set up and may rapidly become unmanageably large for the pilot. The front wing therefore rotates further of its own accord and the machine can become quite out of control of the pilot.

On the other hand steering by means of pivoting the front wing has the great advantage that considerable side momentums are set up, for example as by shutting off an engine of a multi-engine aeroplane, without producing substantial additional resistance.

A "duck" type of aeroplane could also be steered by the usual rudder just behind the main plane, but then the available leverage from the centre of gravity is relatively small and therefore the production of a large side moment would be attended with large additional resistance.

The present invention has for its object to combine the advantages of both forms of steering without their disadvantages so that the heavy isolated side moments which come on are imparted to the pivotal front wing, whereas the ordinary steering operation is effected by a normal rudder behind the centre of gravity.

The accompanying drawing is a perspective of a "duck" type of aeroplane constructed and arranged in accordance with this invention.

The usual steering device for the pilot, generally the foot-board *a* is connected with the rear rudder *b* in exactly the same manner as with ordinary tail-plane type machines. A special device *c* (hand wheel, lever or the like) advantageously self-stopping, near the

pilot pivots the front wing *d* laterally about the axle *e* by means of suitable transmission gear, in order to counteract the above mentioned transverse moment. The pivoting of the front wing is also utilized with respect to the side moment in the same manner as hitherto the elevator fin adjustment has been used with respect to the longitudinal moment in tail-plane type machines. One can for example counteract the large side moment upon shutting off one engine of a multi-engine duck-type machine and then one has available on both sides the possibility of steering unhindered by means of the ordinary rear rudder. In its effect the front wing adjustment corresponds to the body-fin adjustment of the tail-plane type machine, only with the important difference that no additional resistance is set up.

I claim:

An aircraft having a fixed plane and a steering rudder arranged in rear of the center of gravity and the pivotal axis of which rudder is substantially vertical, so that said rudder is movable angularly in a substantially horizontal plane, and also having a pivotally mounted plane arranged in front of the center of gravity, the pivotal axis of said pivotally mounted plane being substantially in the longitudinal axis of the aircraft, so that said plane is movable angularly in a substantially vertical plane transversely of the aircraft and coacts with said rudder to steer and control the aircraft.

In testimony whereof I have hereunto set my hand this 21st day of September, A. D. 1927.

HENRICH FOCKE.
